UNITED STATES PATENT OFFICE

104,669

DESIGN FOR AN INKSTAND

Gustav J. Sengbusch, Milwaukee, Wis.

Application April 9, 1937, Serial No. 68,642

Term of patent 14 years

To all whom it may concern:

Be it known that I, Gustav J. Sengbusch, a citizen of the United States, residing in Milwaukee, county of Milwaukee, and State of Wisconsin, have invented a new, original, and ornamental Design for an Inkstand, of which the following is a specification, reference being had to the accompanying drawing, forming a part thereof.

The figure is a perspective view of an inkstand showing my new design.

I claim:

The ornamental design for an inkstand substantially as shown.

GUSTAV J. SENGBUSCH.
